(57) **CLAIM**

The ornamental design for an elongated element, as shown and described.

DESCRIPTION

FIG. 1 is an isometric view of a front, top, and left side of an ornamental design for an elongated element;

FIG. 2 is a front elevational view of the elongated element of FIG. 1;

FIG. 3 is a rear elevational view of the elongated element of FIG. 1;

FIG. 4 is a right side elevational view of the elongated element of FIG. 1;

FIG. 5 is a left side elevational view of the elongated element of FIG. 1;

FIG. 6 is a top plan view of the elongated element of FIG. 1; and,

FIG. 7 is a bottom plan view of the elongated element of FIG. 1.

The dash-dot-dash lines illustrate boundary lines and form no part of the claimed design.
